UNITED STATES PATENT OFFICE.

GEORGE L. CARPENTER, OF FORT WORTH, TEXAS.

SLEEVE-EXTRACTOR.

1,265,745.

Specification of Letters Patent. Patented May 14, 1918.

Application filed June 5, 1917. Serial No. 172,939.

To all whom it may concern:

Be it known that I, GEORGE L. CARPENTER, a citizen of the United States of America, residing at Fort Worth, in the county of 5 Tarrant and State of Texas, have invented certain new and useful Improvements in Sleeve-Extractors, of which the following is a specification.

My invention relates to a sleeve extractor 10 for use in automobile repair work, and the object is to provide a simple device by which the housing sleeves of roller bearings in the rear axles or axles with differential gearing and for similar purposes and by which the removal is quickly and easily accomplished. 15 Other objects and advantages will be fully explained in the following description and the invention will be more particularly pointed out in the claims.

Reference is had to the accompanying drawings which form a part of this application.

Figure 1 is a side elevation of the improved tool, the handle being raised. Fig. 2 25 is a side elevation of the tool at right angles to the view in Fig. 1, and showing the tool in position to extract the sleeve. Fig. 3 is a plan view of the same. Fig. 4 is a view 30 in the tool connections.

Similar characters of reference are used to indicate the same parts throughout the several views.

The improved tool includes a lifting member 1 and gripping members 2 coöperating therewith. A lever handle 3 is provided for the lifting member 1 and a pry 4 is pivotally connected to the short end of the lever 3. A sliding collar 5 is mounted on the lifting member 1 and the coöperating gripping members 2 are pivotally connected to the collar 5. An adjustable lifting collar 6 is slidably mounted on the lifting member 1 and a link bar 7 is pivotally connected to the 40 collar 6 and to the lever 3. Rack teeth 8 are formed on the lifting member 1. By means of the lifting collar 6, the extracting of the sleeve is made easier because the sleeve can be drawn a portion of the distance out and 45 then the handle lowered so that the collar 6 can engage a tooth farther down on the lifting member 1 which moves freely through the lever 3. This can be repeatedly done until the sleeve is removed. After the first

lift with the lever handle, the lifting mem- 55 ber is drawn up by the collar 6 which engages the rack on the lifting member. The pry 4 is set on the upper part of the housing 9 during operation to coöperate with the lever 3. A pin 12 prevents the member 1 60 from falling out of the lever 3.

In operation, the pry 4 is set on the upper part of the housing. The lifting member 1 is let down through the sleeve and the co- 65 operating gripping members 2 allowed to descend with the lifting member as far as the collar 5 will let the members 2 go down. The lever 3 will be lowered to let the members 2 pass below the lower end of the sleeve 10. The grippers 2 are provided with lugs 70 11 which catch under the bottom of the sleeve 10 when the grippers 2 are forced outwardly by the wedge-shaped shank of the lifting member 1. The shank of the lifting member 1 will pass up through the collar 5 75 without moving the grippers so that the wedge-shape will force the grippers 2 outwardly and thus project the lugs 11 under the sleeve 10. On further operation of the lever handle 3, the member 1 will hold the 80 lugs 11 under the bottom of the sleeve 10 and thus force the sleeve 10 out of the housing 9.

The variation shown in Fig. 4 shows the lifting member 1 without the coöperating collar 6 and link bar 7, and the lifting member 1 is pivoted directly to the lever 3.

Various changes in the sizes, construction, and proportions of the several parts may be made without departing from the scope of the appended claims.

What I claim is:—

1. A sleeve extractor comprising a lifting member provided with a rack formed thereon, a collar slidable on said lifting member, coöperating gripping members pivotally connected to said collar and provided with lugs at their operating ends for engaging a sleeve to be extracted, the lower part of said lifting member being wedge-shaped for expanding said gripping members, a lever pivotally connected to said lifting member, 95 a link bar pivotally connected to said lever and to said collar for causing said collar to engage said rack, and a pry pivotally connected to said lever to bear against the housing of the sleeve.

2. A sleeve extractor comprising a lifting and expanding member, a collar slidable

thereon, coöperating gripping members pivotally connected to said collar, and provided with lugs for engaging a sleeve to be extracted, a lever having an opening to receive the 5 end of said lifting member, said lifting member having a rack formed thereon, a lifting collar slidably mounted on said lifting mem-

ber and adapted to engage said rack, a fulcrum for said lever, and a link bar pivotally connected to said lever and to said lifting 10 collar.

In testimony whereof, I set my hand, this 31st day of May, 1917.

GEORGE L. CARPENTER.
